US00D962299S

(12) **United States Design Patent** (10) **Patent No.:** **US D962,299 S**
(45) **Date of Patent:** **** Aug. 30, 2022**

(54) **TEXTILE MACHINE**

(71) Applicant: **SANTONI S.P.A.**, Brescia (IT)

(72) Inventors: **Ettore Lonati**, Botticino (IT); **Fausto Lonati**, Brescia (IT); **Andrea Lonati**, Brescia (IT)

(73) Assignee: **SANTONI S.P.A.**, Brescia (IT)

(**) Term: **15 Years**

(21) Appl. No.: **29/716,848**

(22) Filed: **Dec. 12, 2019**

(30) **Foreign Application Priority Data**

Jun. 12, 2019 (EM) 006575379-0005

(51) **LOC (13) Cl.** **15-06**

(52) **U.S. Cl.**

USPC **D15/66; D15/72**

(57) **CLAIM**

The ornamental design for a textile machine, as shown and described.

DESCRIPTION

FIG. 1 is a perspective view of a textile machine;

FIG. 2 is a top plan view thereof;

FIG. 3 is a bottom plan view thereof;

FIG. 4 is a front elevational view thereof;

FIG. 5 is a rear elevational view thereof;

FIG. 6 is a left-side elevational view thereof; and,

FIG. 7 is a right-side elevational view thereof.

The broken lines in the drawings depict portions of the textile machine that form no part of the claimed design.

1 Claim, 7 Drawing Sheets
